(57) **CLAIM**

The ornamental design for a UV lamp with bracket, as shown and described.

DESCRIPTION

FIG. 1 is a top view of a UV lamp with bracket, showing our design;

FIG. 2 is a bottom view thereof;

FIG. 3 is a rear view thereof;

FIG. 4 is a front view thereof;

FIG. 5 is a right side view thereof;

FIG. 6 is a left side view thereof;

FIG. 7 is a top perspective view thereof; and,

FIG. 8 is a bottom perspective view thereof.

The broken line showing in the figures shows portions of the UV lamp with bracket that form no part of the claimed design. The UV lamp with bracket is shown with symbolic breaks in its length. The appearance of any portion of the article between the break lines forms no part of the claimed design.

1 Claim, 5 Drawing Sheets
